UNITED STATES PATENT OFFICE

160,567

MUG OR SIMILAR ARTICLE

Dale Wylie, Cleveland Heights, Ohio

Application October 22, 1949, Serial No. 5,652

Term of patent 14 years

(Cl. D36—8)

To all whom it may concern:

Be it known that I, Dale Wylie, a citizen of the United States, residing at Cleveland Heights, in the county of Cuyahoga and State of Ohio, have invented a new, original, and ornamental Design for a Mug or Similar Article, of which the following is a specification, reference being had to the accompanying drawings, forming a part thereof.

Figure 1 is a perspective view; Figure 2 is an elevational view; and Figure 3 a plan view of a mug or similar article, embodying my new design.

The dominant feature thereof resides in the handle which is shown in full lines.

I claim:

The ornamental design for a mug or similar article, substantially as shown and described.

DALE WYLIE.
